[57] CLAIM

The ornamental design of a pneumatic gun and nozzles therefor, as shown and described.

DESCRIPTION

FIG. 1 is a right side view of a pneumatic gun with an attached nozzle in accordance with the present invention;

FIG. 2 is a right side view of the pneumatic gun depicted in FIG. 1 with the lever at the top depressed allowing the nozzle holder with the nozzle therein to pivot forward for removal of the nozzle;

FIG. 3 is a front perspective view of the pneumatic gun depicted in FIG. 1 without a nozzle;

FIG. 4 is a rear view of the pneumatic gun depicted in FIG. 3;

FIG. 5 is a left side view of the pneumatic gun depicted in FIG. 3; and,

FIG. 6 is a bottom view of the pneumatic gun depicted in FIG. 3.

FIG. 1

FIG. 2

FIG. 3

FIG. 4

FIG. 5

FIG. 6
